(57) **CLAIM**

The ornamental design for a footwear puller, as shown and described.

DESCRIPTION

FIG. 1 is a front perspective view of a first embodiment of a footwear puller showing my new design;

FIG. 2 is a front view thereof;

FIG. 3 is a rear view thereof;

FIG. 4 is a right side elevational view thereof;

FIG. 5 is a left side elevational view thereof;

FIG. 6 is a top view thereof;

FIG. 7 is a bottom view thereof;

FIG. 8 is a front perspective view of a second embodiment of a footwear puller showing my new design;

FIG. 9 is a front view thereof;

FIG. 10 is a rear view thereof;

FIG. 11 is a right side elevational view thereof;

FIG. 12 is a left side elevational view thereof;

FIG. 13 is a top view thereof; and,

FIG. 14 is a bottom view thereof.

The oblique shading lines in FIGS. 8-14 indicate an opaque refractory surface coating that conforms to the shape of the elements and features of the footwear puller illustrated therein.
